REFRIGERATING MECHANISM

Frank R. West, Highland Park, Mich., assignor to
Copeland Products, Inc., a corporation of
Michigan

Application December 4, 1929. Serial No. 411,401

8 Claims. (Cl. 62—4)

This invention relates to refrigerating mechanism of the mechanical household type, and particularly to means for controlling the temperature produced thereby, the principal object being the provision of a manually controllable mechanism mounted for convenient operation and so constructed as to enable the temperature produced in the refrigerator cabinet, by the refrigerator mechanism, to be easily, quickly and simply varied.

Another object is the provision of a novel manual control for the temperature control mechanism of a mechanical refrigerating mechanism.

Another object is to provide a new and novel support for the temperature control bulb of a mechanical refrigerating mechanism.

Another object is to provide a novel supporting means for the control bulb of a mechanical refrigerating mechanism, whereby frosting of the return line is substantially eliminated.

Another object is to provide in combination with a mechanical refrigerating mechanism having a temperature control bulb, a bracket having direct metallic contact with the temperature control bulb and with the discharge side from the evaporator, whereby any change of temperature at the discharge end of the evaporator is readily and quickly transmitted to the temperature control bulb.

Further objects of the present invention will be obvious from the following specification, reference being had to the accompanying drawing, in which:

Fig. 1 is a front elevation of a mechanically cooled refrigerating cabinet, a portion of which is broken away to illustrate the mechanism contained therein.

Fig. 2 is an enlarged fragmentary view taken as on the line 2—2 of Fig. 1 showing the upper portion of the brine tank with the control mechanism mounted thereon, the near face of the brine tank being broken away to illustrate the construction of the parts within the same.

Fig. 3 is a plan view of the mechanism shown in Fig. 2.

Fig. 4 is an end elevation taken from the left hand side of Fig. 2.

It has been found desirable in connection with mechanical refrigerating mechanism for household use to provide manually operable means whereby the temperature produced by the refrigerating mechanism within the cooling compartment may be easily and quickly varied. The reason is that under normal conditions a relatively moderate temperature only is required

within the box to properly preserve the food stuff contained therein, and the higher the temperature that may be maintained in the box the more economical the operation of the refrigerating mechanism becomes. However, at relatively infrequent periods, it is desired to obtain a relatively low temperature within the cooling compartment, and particularly in the freezing compartment, in order to quickly freeze ice, desserts, or other such materials, the freezing of which would take too long, or which might not freeze at all at the temperature normally maintained in the cooling compartment. These lower temperatures are undesirable under normal conditions because of the increased expense in operation of the refrigerating mechanism and the resulting unnecessary and undesirable freezing of the bulk of the articles normally kept in the cabinet. It is to this type of control that the present invention primarily relates.

I am aware that heretofore a number of constructions have been proposed for effecting the above result, but I have found that in those constructions the operation of the temperature control bulb which controls the switch to the motor is entirely too dependent upon the temperature within the cooling compartment or within the brine tank, with the result that where the temperature in the cooling compartment or in the brine tank does not respond quickly enough to the increased flow of refrigerant through the expansion chamber occasioned by moving the control to produce the low temperature, liquid refrigerant is often carried through the discharge side of the expansion chamber back to the compressor, and this not only freezes up the compressor but represents a waste in the cost of operation, inasmuch as such refrigerant which finds its way out of the evaporator in the liquid state is lost as far as cooling effect is concerned. In this respect it will be obvious that when the evaporator is once filled with liquid refrigerant, any further liquid refrigerant which is pumped into the evaporator, and thereby causes a displacement of liquid refrigerant into the discharge passage from the evaporator, will have no beneficial effect whatsoever in tending to produce a lower temperature in the cabinet, for when the evaporator is completely filled with liquid refrigerant, it is in the highest state of heat absorption that it may reach. Accordingly, it is the further object of the present invention to provide a means whereby the possibility of continued operation of the refrigerating mechanism after liquid refrigerant has begun to be discharged

from the evaporator, will be eliminated, and the operation of the refrigerating mechanism will be quickly stopped upon such occurrence.

Referring now to the accompanying drawing, I show in Fig. 1 a refrigerator cabinet 10 having an upper compartment 11 and a lower compartment 12. The lower compartment 12 which is normally closed by the louvred cover or door 13 contains a motor 14, a compressor 15 driven by the motor 14, a condenser 16 connected with the discharge side of the compressor 15, and a receiver 17 for storing the refrigerant condensed by the condenser 16.

The upper chamber 11 is closed by the doors 18 and 58. Behind the door 18 when closed and in the upper portion of the chamber 11 is a baffle member 19 as in conventional constructions, behind which is located the brine tank 20 (the Figs. 2 to 4, inclusive) into which project one or more freezing trays 21 withdrawable from the face of the baffle 19. Referring now to Figures 2 to 4, inclusive, the brine tank 20 is shown as of conventional construction, it comprising a closed hollow sheet metal container in which the coils 22 serving as the evaporator for the refrigerating mechanism are housed. A conventional type of pressure-actuated expansion valve 23 is shown mounted on the upper surface of the brine tank 20, its discharge side being connected to the intake side of the expander or evaporator 22 which extends directly from the expansion valve 23 to a point adjacent the bottom of the brine tank 20. The intake side of the expansion valve 23 is connected to the pipe or tube 25 which is directly connected to the receiver 17. The outlet end 26 of the evaporator 22 is supported in the bracket member 27 which projects into the upper end of the brine tank 20, the bracket member 27 being provided with an opening serving as a passage connecting the evaporator 22 with the tube 29 which leads to the suction side of the compressor 15. The bracket member 27 which is directly connected to the shell of the brine tank 20, as by soldering brazing or other suitable means, projects upwardly from the top face of the brine tank 20, and is there provided with a bore 30 extending upwardly towards the baffle 19 at the front of the brine tank. The bracket 27 is provided with a slot 31 leading into the bore 30 in axially parallel relation thereto, and screws 32 are provided for drawing the sides of the slot together to thereby effect a clamping action on a member received within the bore 30 in the well-known manner.

Received in the bore 30 and clamped therein against movement by the screws 32 is the bulb 33 of a conventional type of temperature-actuated switch mechanism 34, which is connected to the motor 14 by means of a cable such as 35. The particular type of temperature control mechanism shown is of well-known construction and is provided with a rotatable member 35, suitable rotation of which will vary the temperature at which the control bulb 33 will cause the switch mechanism to be operated to start or stop the motor 14.

In accordance with the present invention, I fix to member 35 a pair of diametrically oppositely and outwardly projecting lugs or ears 37, each of which is apertured as at 38. A bracket 70 40 secured to the top face of the brine tank 20 immediately behind the baffle 19, rotatably supports the shaft 41 which projects out through the baffle 19 and is there provided with a head 42 having a pointer 43 and operating handle 44. 75 Suitable indicia 45 are provided on the front

face of the baffle 19 in cooperative relationship with the pointer 43. The rear end of the shaft 41 is flattened off and non-rotatably supports thereon a rearwardly extending U member 45, the free ends of which are reduced as at 46 and are slidably received within the apertures 38 in the ears 37. This effects a universal connection between the head 42 and the rotatable member 36 on the control whereby rotation of the head 42 by the handle 44 will act through the shaft 41 and U shaped member 45 and thence through the ears 37 to cause rotation of the member 36. As previously described, rotation of the member 36 will act to vary the temperature at which the bulb 33 will cause the switch mechanism 34 to operate to start or stop the motor 14. This mechanism, therefore, provides a simple and effective manual control for the switch mechanism 34.

It will be noted that the bracket 27, which is preferably formed of a metal having high heat conductivity, forms a portion of the return passage between the evaporator 22 and the compressor 15. It will also be noted that the bore 30 in which the bulb 33 is received and supported is formed as close as possible to the passage 28, this necessitating the bulb 33 being positioned in slightly angular relationship to the top face of the brine tank 20, and the provision of the slip connection between the shaft 41 and the member 36. The reason for this part of the construction is that it is desired to get a direct metallic contact over the shortest path possible between the control bulb 33 and the refrigerant being discharged from the evaporator 22.

By forming the passage 28 and the bore 30 for the bulb 33 in closely adjacent relationship, as described, when the head 42 is turned to produce a relatively low temperature within the refrigerator cabinet, should the refrigerating mechanism, in an endeavor to produce such low temperature, begin to discharge liquid refrigerant through the discharge end 26 and passage 28, such liquid refrigerant in passing through the passage 28 will immediately cause a material drop in the temperature of the bracket 27, and this drop in temperature will be transmitted directly through the metal of the bracket 27 to the bulb 33 which, being in a direct metallic contact with the bracket 27, will immediately be operated to move the switch mechanism 34 to shut off the motor 14. Thus any material discharge of liquid refrigerant through the passage 28 will be accompanied almost immediately by a stopping of the motor 14, and consequently further discharge of liquid refrigerant from the evaporator 22 will be prevented.

It is, of course, desirable, in order to realize the fullest benefits of the present invention, that the evaporator 22 be so constructed that until it is substantially full of liquid refrigerant there will be no opportunity for discharge of liquid refrigerant through the passage 28. In this connection it is to be noted that there are a number of evaporators now on the market in which this condition will obtain.

Formal changes may be made in the specific embodiment of the invention described without departing from the spirit or substance of the broad invention, the scope of which is commensurate with following claims.

I claim:

1. In a refrigerating mechanism, in combination, an evaporator, a bracket having a passage therein forming a part of the discharge passage

- for the evaporator and constructed of metal having high heat conducting properties, and temperature control means including a temperature responsive bulb disposed in direct metallic contact with said bracket and means associated with said bracket for clamping the latter upon said bulb. 5
2. In a mechanical refrigerating mechanism, in combination, a concealing baffle, an evaporator and a temperature control device located behind 10 said baffle, said temperature control device comprising a temperature responsive bulb, a switch mechanism operated thereby and a movable member for varying the effect of said control bulb on said switch mechanism, a direct metallic contact 15 between the discharge side of said evaporator and said temperature control bulb, and means operable from the front face of said baffle for controlling the position of said movable member. 20
3. In a mechanical refrigerating mechanism, in combination, a brine tank, a metallic bracket having direct metallic contact with said brine tank secured to the other face thereof, an evaporator within said brine tank discharging through said bracket, a temperature controlled unit for said 25 mechanism comprising a temperature responsive bulb, a switch mechanism supported and actuated thereby and a manually adjustable member for varying the operation of said switch mechanism by said temperature responsive bulb, said temperature responsive bulb being supported in direct metallic contact with said bracket, a baffle for concealing the face of said brine tank, a shaft extending through said baffle in approximate alignment 30 with said control unit, manually operable means exterior to said baffle for controlling the rotatable position of said shaft, and means operatively connecting said shaft with said movable member whereby the movable position thereof may be controlled from a point exterior to said baffle. 35
4. The combination with a refrigerating mechanism including a compressor, condenser, expansion valve and evaporator for a refrigerant, of a bracket for supporting the outlet end of said evaporator, a thermo-responsive switch unit supported 40 by said bracket and having the thermo-responsive element thereof independent of but in contiguous relation to said outlet. 45
5. The combination with a refrigerating mechanism including a compressor, condenser, expansion valve and evaporator for a refrigerant, of a bracket for supporting the outlet end of said evaporator, a thermo-responsive switch unit supported by said bracket in such manner as to have the thermo-responsive element thereof in contiguous relation to said outlet and adjustable means associated with said unit for varying the actuation of said switch relative to the response of said thermo-element. 50
6. The combination with a refrigerating mechanism including a compressor, condenser, expansion valve and evaporator for a refrigerant, of an element of good heat-conducting material constituting the outlet end of said evaporator, extensions on said element constituting a bracket and a thermo-responsive switch unit supported by said bracket in such manner as to have the thermo-element of said unit in contiguous relation to but independent of said outlet. 55
7. The combination with a refrigerating mechanism including a compressor, condenser, expansion valve and evaporator for a refrigerant, of an element of good heat-conducting material constituting the outlet end of said evaporator, extensions on said element constituting a bracket, a thermo-responsive switch unit supported by said bracket in such manner as to have the thermo-element of said unit in contiguous relation to said outlet and regulating means for said switch associated with said unit. 60
8. A mechanical refrigerating system comprising a refrigerant condensing unit having an electrical motor, a refrigerant evaporating unit having an electrical switch mounted thereon for controlling said condensing unit motor, an adjustable temperature control device associated with said evaporating unit for operating said switch, a concealing baffle disposed in front of said evaporating unit and projecting therebeyond in front of said switch and said temperature control device, and adjusting means mounted on said baffle and accessible from the front surface thereof for varying the operative relation of said switch and said temperature control device. 65
